[57] CLAIM

The ornamental design for a frame for digital clock, as
shown and described.

DESCRIPTION

FIG. 1 is a front perspective of a frame for digital clock
in accordance with the present invention;

FIG. 2 is a front elevational view of the frame for digital
clock shown in FIG. 1;

FIG. 3 is a rear elevational view of the frame for digital
clock shown in FIG. 1;

FIG. 4 is a right side view (the left side view is the
mirror image of the right side view) of the frame for
digital clock shown in FIG. 1;

FIG. 5 is a top view of the frame for digital clock shown
in FIG. 1; and,

FIG. 6 is a bottom view of the frame for digital clock
shown in FIG. 1.

FIG. 1

FIG. 2

FIG. 4

FIG. 3

FIG. 5

FIG. 6
